[57] CLAIM

The ornamental design for a flowmeter, as shown and described.

DESCRIPTION

FIG. 1 is a front view of a flowmeter showing our new design;

FIG. 2 shows a left side view of the flowmeter of FIG. 1a;

FIG. 3 shows a top view of the flowmeter of FIG. 1a; FIG. 4 shows a bottom view of the flowmeter of FIG. 1a;

FIG. 5 shows a rear view of the flowmeter of FIG. 1a. The right-hand side view, which has been omitted for purposes of simplicity, is identical to the left-hand side view, shown in FIG. 2.

FIG. 1

FIG. 2

FIG. 3

FIG. 4

FIG. 5
